AQUA SLED

Tak Kimura, 704 W. 56th St., Los Angeles, Calif.

Filed Mar. 22, 1960, Ser. No. 59,828

Term of patent 14 years

(Cl. D71—1)

Figure 1 is a perspective view of an aqua sled showing my new design;

Figure 2 is a front view thereof;

Figure 3 is a side elevational view thereof, and
Figure 4 is a bottom plan view thereof.

What is claimed is:

The ornamental design for an aqua sled, substantially as shown.
